Des. 210,647

Patented Mar. 26, 1968

210,647

STRING BEAN SNIPPER

Joe R. Urschel, 202 Michigan Ave.,
Valparaiso, Ind. 46383

Filed May 26, 1966, Ser. No. 2,441

Term of patent 14 years

(Cl. D95—1)

Fig. 1

Fig. 2

Fig. 3

Fig. 4

FIGURE 1 is a front elevational view of a string bean snipper, showing my new design, the fragmentary broken lines showing a rod for illustrative purposes only;

FIGURE 2 is a side elevational view thereof;

FIGURE 3 is a rear elevational view thereof; and

FIGURE 4 is a top plan view thereof, a lower bracket member having been omitted therefrom for convenience of illustration.

I claim:

The ornamental design for a string bean snipper, as shown and described.
